WRINGER

Charles W. Williams, Cleveland, Ohio, assignor to
Automatic Safety Wringer Company, a partnership

Application February 8, 1937, Serial No. 124,531

13 Claims. (Cl. 68—253)

This invention relates to washing machine wringers and more particularly to wringers designed primarily for safety in operation.

This wringer is of the multiple roll type and during the wringing operation employs two pressure rolls and a third roll cooperating with one of the pressure rolls to provide an intake bite. The construction is so arranged that when clothes of predetermined thickness are fed to the intake bite, the operation of the wringer automatically ceases.

It has been the general object of my invention to construct a three-roll wringer in which one roll constantly acts as the pressure roll and in which the other two rolls coact therewith, each of them alternately acting as the feed roll or a pressure roll, depending on the direction from which clothes are fed.

In general I accomplish this by mounting three rolls in triangular relation, one on top and two below. Pressure applying means to set up the requisite wringing pressure is provided which is shiftable to coact with either of the lower rolls as desired in order that the same may cooperate with the top roll to wring clothes. The lower roll, which is not engaged by the pressure creating means, is free to act as the auxiliary roll. As above indicated, upon the reversal of the direction of the feeding of clothes the roll which has been acting as the auxiliary roll becomes the pressure roll and similarly the pressure roll becomes the auxiliary roll.

A further object of my invention has been to use the aforementioned construction in such manner that movement of the roll acting as the auxiliary away from its cooperating roll will stop the operation of the wringer, preferably by disconnecting the driving means from the rolls.

Other objects of my invention will become apparent from the specification following and from the drawings appended hereto. The novel features of my invention are set forth in the claims.

Referring now to the drawings:

Fig. 1 is a perspective of a wringer embodying the features of my invention;

Fig. 2 is a transverse section through the center of the wringer showing the construction adjacent the supported end of the wringer;

Fig. 3 is a horizontal section across the wringer as indicated by the line 3—3 of Fig. 2;

Figs. 4 and 5 are cross-sections through the wringer as shown by the lines 4—4 and 5—5, respectively, on Fig. 2 with parts removed;

Fig. 6 is a fragmentary section as indicated by the line 6—6 on Fig. 2 showing the manner of driving one lower roll from the other, together with the means for supporting the guide;

Figs. 7 and 8 are fragmentary sections showing mechanism for disconnecting the power drive.

Figs. 9 and 10 are schematic showings of the positions occupied by the lower roll supporting bars as clothes are fed from each side of the wringer.

5 Fig. 11 is a detailed view of the mechanism for shifting the drain board.

As heretofore mentioned and as shown in Fig. 4, the wringer in general comprises three wringing rolls 10, 11 and 12 arranged in triangular relationship. A guide bar 15 extends the length of the rubber rolls and coacts with the two lower rolls to insure the passage of clothes through the wringer rather than downwardly between the rolls. Pressure spring mechanism, as shown in 10 Fig. 5, is pivotally carried by the bar 20 and is shiftable to coact with either lower roll desired.

15 The wringer, referring to Fig. 1, comprises a head portion 22 and a main frame 24 carrying pivotally thereon, on a longitudinal axis, a sub-frame 25. The head shown in Fig. 2 carries a downwardly extending stub shaft 28 adapted to be connected with the power drive from the washing machine when the wringer is mounted in place on the wringer post carried by the machine. The stub shaft 28 carries a bevel gear 30, which in turn drives in opposite directions a pair of bevel gears 33 and 34. A gear 33 is pinned to the shaft 35, which, as shown in Fig. 2, at its right-hand end, terminates in a head 37 carrying a plurality of clutch teeth.

20 The bevel gear 34 is pinned to a sleeve 40 which is rotatably carried on the shaft 35 and prevented from longitudinal slippage by the head member 42 which is abutted at one side by the gear hub, and on the other by a ring 43 carried by the sleeve. At its right-hand end the sleeve 40 is provided with a plurality of clutch teeth 45. It will be apparent at once that the teeth of the sleeve 40 rotate in a direction opposite to 25 that of the teeth of the shaft 35. In order to facilitate assembly the head is open at the left-hand end and closed with a cover plate 23.

25 A gear is carried idly on the shaft 35 and meshes with the gear carried by the upper roll 45 to provide a power drive for the wringer. This gear, designated at 50, is provided at each side with an elongated hub, the ends of the hub being toothed to engage the teeth on the sleeve 40 and shaft 35 respectively. An annular ring 51 for engagement by a shifting yoke is cut in the left-hand side of the hub, as shown in Fig. 2. A yoke 52 having pins engaging the annular recess 51 is pivotally carried at 54 by the head.

30 To manually shift the gear 50 to reverse the wringer or to stop rotation of the same, a manually operated rock arm 55 is pivoted to the head at 56. A link 57 connects the arm with the yoke 52. Thus in the position shown in Fig. 2, the gear 50 engages the teeth of the sleeve 40. When 35 the rock arm 55 is horizontal, the gear 50 is

disengaged from both sets of teeth. When the arm 55 is rocked to the left (Fig. 2), the gear, through the yoke 52, engages the teeth of the shaft 35 and the wringer drive is reversed.

The upper roll gear, designated at 60 and rotatably driven by the gear 50, is of considerable axial thickness to insure a satisfactory drive for any position of the gear 50. The gear 60 is carried on the shaft 62 of the roll 10, which shaft is journaled at 63 in the end of the sub-frame 25 and is also journaled in two cross-arms 64 extending across the subframe 25 and each of which cross-arms abuts an end of the roll carried thereby to prevent lateral shifting of the same.

Sub-frame 25, as heretofore stated, is longitudinally pivoted on the frame 24. This pivot comprises a pair of arms 65 extending downwardly from the sub-frame and pivoted to the main frame at 68. A manually releasable latch 70 normally retains the sub-frame 25 in closed position and also permits the same to be readily opened.

As clothes are ejected from the rolls after wringing there is a tendency for them to wrap around the rolls and become tangled therewith. To prevent this with regard to the upper roll 10, I provide a stripper 72 (Fig. 4) having pins reciprocable in mating slots of the cross-frame member 75 of the sub-frame 25. The weight of the stripper retains it in contact with the roll and reciprocation is provided to compensate for any irregularities in the roll surface.

Each of the lower rolls is supported in such manner that it may move away from the upper roll when acting either as a pressure or as an auxiliary roll. Thus, as shown in Figs. 3 and 5, the roll 12 is provided with an elongated shaft 80 which is journaled at each side of the roll in the free ends of a pair of bars 82 pivoted to the wringer frame 24 at 84. The roll 11 is provided with a shaft 85, which is similarly carried in the free ends of the pair of pivoted bars 86 supported by the frame at 88. As shown in Fig. 5, the bars 86 are goose necked upwardly where they extend across the shaft 80 and thus are able to rock downwardly without disturbing that shaft. The free ends of the bars 82 and 86 are guided between shoulders 84 and 89 of the frame to prevent sidewise movement and are limited in upward movement by overlying ledges 91 merging with the shoulders 89.

Pressure is applied to one of the lower rolls at a time through a pair of pressure springs to render the same effective as a wringing roll. One end of each of the two pressure springs 90 bears against a block 92 fixed to the bar 20 and provided with a nub extending upwardly inside the spring to retain the same in position. The opposite end of the spring 90 bears against the block 94, which is similarly provided with a nub to retain the spring. A bolt 95 passes from one block to the other to prevent excessive elongation of the spring upon disassembly and to link both blocks 94 to the bar 20 to permit rocking the entire assembly as a unit.

Each of the two blocks 94 carries outwardly extending stubs on opposite sides thereof, respective stubs acting with the bars 82 and 86 respectively to apply wringing pressure thereto, as shown in Figs. 2 and 5. The under sides of these pairs of bars are oppositely recessed to provide cam surfaces and the tops of the respective stub portions of the blocks 94 act thereagainst. As best shown in Fig. 5, when the spring is in the

position there shown, the ends of the two blocks 94, are tight against the cam surfaces of bars 86 and thus force the roll 11 into wringing relation with the roll 10. At this time, however, due to the peculiar shape of the cam recesses, there is sufficient clearance above the arms or stubs of the blocks 94 lying in coacting relation with the bars 82 to permit the bars to rock freely downwardly, thus permitting the roll 12 to act as an auxiliary roll. When the spring mechanism is shifted to the right of the position shown in Fig. 5, the shapes of the cam recesses in the pairs of bars 82 and 86 result in the former being forced upwardly to create a pressure roll bite between the rolls 10 and 12. At the same time the clearance in the cam recesses in the two bars 86 permits the same to rock downwardly freely and the roll 11 to act as an auxiliary roll. The two spring mechanisms, one at each end of the lower rolls, are shiftable as a unit with the bar 20.

It will thus be apparent from the foregoing description that, depending upon the position of the spring mechanism, one of the lower rolls, through the medium of its pivoted supporting bar, is urged upwardly to coact with the roll 10 to provide a pressure bite and at the same time the other lower roll is freely pivoted with respect to the roll 10 to provide an auxiliary roll bite. Four light springs 100 connect the ends of each of the four lower roll supporting bars with the frame at a point above each bar. Thus, when the wringer mechanism is in the position of Fig. 5 and the two bars 86 are prevented from downward movement, unless they compress the two pressure springs, the bars 82 are restrained against downward movement only as they tension the respective springs 100 which support them at their ends. In this manner it is possible to create sufficient spring pressure between the roll acting as an auxiliary and the roll 10 to insure a satisfactory feed bite and at a low enough pressure to avoid injury to the operator's hands if they pass into the auxiliary bite and further permit ready withdrawal of the hands if so caught.

It has been found desirable to positively drive the lower roll acting as the auxiliary from the lower roll acting as a pressure roll, the latter of course being effectively driven through the clothes passing therebetween due to the wringing pressure between it and the upper driven roll. To this end, three interengaging gears 105, 106 and 107 are provided, the first and last of which are pinned to shafts 85 and 80, respectively. The gear 106 is supported on a shiftable axis defined by links 108, 109, pinned together at one end by shaft 110 carrying the gear 106 and at their other ends each idly carried by the lower roll shafts. As the positions of the lower rolls shift the shaft 110 must remain in coacting relation with each roll due to the connecting links, and thus the one lower roll is always driven by the other.

To prevent passage of clothes downwardly between the lower rolls and insure their passage through the two wringer bites, the guide 15 is provided. This guide, as shown in Fig. 3, is also carried by the links 108 and 109, of which there is a set at each end of the wringer. Here again, as the positions of the lower rolls shift, the guide remains in substantially the same coacting position with regard to each lower roll due to the path of its movement defined by the supporting links. Thus the guide is always in

position to properly strip clothes passing thereto.

Strippers are provided for each of the lower rolls which function in a manner similar to the stripper 72 carried by the roll 10. A shaft 115 is provided on each side of the wringer, as shown in Fig. 4; each of which pivotally supports a stripper plate 116, bearing against each roll, as shown. Springs 116' are provided at each end of the plates 116 which encircle the shafts 115 and bear against the plates in such manner that the same are each retained lightly in contact with the coacting roll. Thus, as the position of each roll shifts the end of the plate 116 coacting therewith follows the roll contour and insures a continuous and positive stripping action for clothes leaving the wringer, as well as facilitating the feeding of clothes to the wringer.

The shafts 115, which support the strippers 116, also serve to carry the mechanism by which the rotation of the rolls is stopped when an excess thickness of material is fed thereto. As above indicated, if the operator's hands become caught between the two rolls providing the auxiliary bite, it is comparatively easy to withdraw them because of the light pressure tending to hold them together which results from the action of the springs 100. In rare instances, however, if an operator's fingers should become caught in the pressure roll bite, it is essential that the wringer be immediately stopped. This is effected because, under such conditions, the lower roll acting as the auxiliary is separated from its coacting roll by a comparatively large amount. The release mechanism, by which the roll rotation is stopped, is best shown in Figs. 2, 3, 4, 7 and 8. As there shown, each of the shafts 115 supports a pair of rock arms 120 which, as best shown in Fig. 3, underlie each of the lower roll shafts at the ends thereof. The shafts 115 are journaled in the ends of the wringer adjacent the head, as shown in that figure, and each supports an elongated, downwardly curved rock arm 125 and 126. It thus follows that if either end of one of the lower rolls is urged downwardly as by the operator feeding her hands thereto, an arm 120 will be rocked, which in turn rocks the respective arm 125 or 126.

Rocking of one of the downwardly curved arms acts to shift the gear 50 out of engagement with whichever set of teeth it may engage. To this end a yoke 130 is pivoted to the frame at 131 and embraces the annular recess 51 of the spur gear 50. Connection is made with the recess 51 by the same pins which connect the yoke 52 therewith. In effect this provides a double yoke engaging the clutch at a single pair of opposite points. The yoke 130 extends downwardly past the pivot point and terminates in a flat shoulder. To this shoulder is suitably fastened a leaf spring 135 which extends outwardly therefrom to provide a unit of substantially T-shape. Fig. 2 shows the mechanism just described in position to establish a drive through the sleeve 40 to the spur gear 50 and in turn to the roll 10. The same figure shows the ends of the respective arms 125 and 126 in idle position before they are moved to stop the wringer. As there shown, the arm 125 when rocked downwardly by the shaft of the roll 11 stops the wringer. The roll acting as the auxiliary may drop any desired distance before it actuates the release, although I have found that a convenient working distance is $\frac{1}{8}$ of an inch, and during an additional $\frac{1}{8}$ of an inch of auxiliary roll drop, the clutch mechanism is disengaged. Referring again to Fig. 2, when the roll

12 acting as the auxiliary drops $\frac{1}{8}$ of an inch, the end of the arm 125 is in contact with the upwardly facing portion of the leaf spring 135. The spring is stiff enough so that an additional downward movement of the arm rocks the yoke 130 about the pivot 131 and moves the gear 50 to idle position, thereby stopping the roll rotation. By operation of the latch 70, the wringer top may be conveniently opened and all pressure relieved from the roll.

It is sometimes desirable to wring a heavy blanket which is ordinarily of sufficient thickness to actuate the roll stopping mechanism. Under such circumstances, if the roll rotation stops, it is only necessary to rock the arm 55 in the desired direction which manually reestablishes a roll drive between the gear 50 and sleeve 40 or shaft 35, as may be desired. This is possible although one of the arms 125 or 126 be rocked to maintain the drive in neutral. Due to the resiliency of the leaf spring 135, an amount of play is established between the release arms and the yoke 130 to permit rocking of the latter without substantial upward displacement of the release arm. The manual control furnished by the rock arm 55 is a further advantage because clothes may not only be fed through the wringer in the direction in which they were started, but the wringer may be reversed to eject clothes at the auxiliary roll bite.

It is desirable to simultaneously shift the pressure spring mechanism 90 and the wringer drainboard. As shown in Fig. 11, a drainboard designated at 140 is pivoted to the frame at 141 and above the pivot point carries pin 142. This pin is engaged by fork 145 secured to the bar 20. Pivotedly carried by the shaft 62 and at opposite ends of the pressure roll 10 are arms 150 forked at the bottom and extending upwardly through the wringer top and riding in slots therein. The forked end at the bottom of each member 150 engages the block 94 which provides a seat for the upper end of the respective pressure springs 90. A suitable handle 152 connects the exposed ends of the arms 150. Thus, shifting the handle from one side of the wringer to the other will shift the pressure spring mechanism from coaction with one lower roll to coaction with the other lower roll. Simultaneously the drainboard 140 will be shifted by the fork 145 to its proper position. By properly shifting the arm 55, roll rotation may be established in the desired direction, whereupon clothes may be fed between the auxiliary rolls and the water wrung therefrom as they leave the pressure rolls.

To prevent an excessive amount of water from splashing into the ends of the wringer a vertical baffle 155 is provided at each end of the rolls. These baffles are cut away near the shafts of the three rolls in order that there be no interference with the up and down movement of the rolls or the guide 15.

Other modes of applying the principle of my invention may be employed instead of the one explained, change being made as regards the mechanism herein disclosed, provided the means stated by any of the following claims or the equivalent of such stated means be employed.

I therefore particularly point out and distinctly

70 claim as my invention:

1. In a wringer with three rolls positioned to provide a pressure bite and an auxiliary bite, a frame, said rolls carried in said frame with one roll contacting each of the other two to provide a pair of roll bites, shiftable means to establish

wringing pressure at either of said roll bites, and positive means to drive the roll not acting as a pressure roll through the remaining of the other two rolls.

2. In a wringer, a pair of rolls, resilient means to apply wringing pressure to said rolls, means including a resilient member acting automatically on feeding an excess thickness of material to the wringer to stop the operation of said wringer, and means to manually reestablish the operation of the wringer to feed said excess thickness of material by flexing said resilient member while permitting said stopping means to remain in condition to stop the operation of the wringer upon release of the manual means.

3. In a wringer, a frame, a pair of pressure rolls carried by said frame, resilient means to apply wringing pressure to said rolls, a member shiftable away from one of said pressure rolls, power means to drive said rolls, a power connection between said power means and said rolls, mechanism including a resilient member linking said power connection and said first member to disconnect the power connection upon movement in excess of a predetermined amount of the first member away from its coacting roll, and means to manually reestablish said power connection without substantially moving said first member due to flexing of said resilient member.

4. In a wringer, a frame, three rolls mounted in said frame with their axes triangularly spaced from each other to provide between said rolls a pair of roll bites, resilient means to maintain wringing pressure between two of said rolls, means to shift said resilient means to establish wringing pressure between one of said two rolls and the third roll, and release mechanism adapted to be actuated when a predetermined thickness of material is fed to the wringer to stop the operation of said wringer.

5. In a wringer, a frame, three rolls carried in said frame to provide a pair of roll bites, means to establish wringing pressure between the two rolls forming one of said bites or between the two rolls forming the other of said bites as desired, power means to drive said rolls, means to shift said pressure establishing means to provide wringing pressure between either pair of rolls as desired, a separable power connection between said power means and said rolls, and mechanism operative when a predetermined thickness of clothes is fed between the pair of rolls that does not form the wringing pressure bite to disconnect said separable connection.

6. In a wringer, a frame with one roll rotatably carried thereby, two pairs of overlapping arms pivotally carried by said frame, a roll carried by each pair of arms in such relation that one of the arm carried rolls lies between the other roll and the pivot for the arms carrying the other roll, said three rolls cooperating to provide a pair of roll bites.

7. In a wringer, a frame with a roll rotatably carried thereby, two pairs of overlapping arms pivotally carried by said frame, a roll carried by each pair of arms in such relation that one of the rolls carried by one pair of arms lies between the other roll and the pivot for the arms carrying the other roll, spring means pivotally carried beneath said arms to establish wringing pressure between a pair of rolls by bearing against said arms and shiftable from coaction with one pair

of arms to coaction with the other pair of arms.

8. In a wringer, a frame with a roll rotatably carried thereby, two pairs of overlapping arms pivotally carried by said frame, a roll carried by each pair of arms in such relation that one of the rolls carried by one pair of arms lies between the other roll and the pivot for the arms carrying the other roll, and means operative when one of said arm supported rolls is separated a predetermined distance from said rotatably carried roll to stop the feeding of clothes through said wringer.

9. In a wringer, a frame, a roll rotatably carried thereby, two other rolls each contacting said first roll and shiftably carried in said frame to provide a pair of roll bites, a guide substantially between said three rolls and adapted to carry clothes from the bite between said first roll and one of the shiftable rolls to the bite between said first roll and the other of said shiftable rolls, and links connecting said guide with each of said shiftable rolls to retain the guide in proper operative position when said rolls are shifted.

10. In a wringer, a frame, a roll rotatably carried thereby, two other rolls each contacting said first roll and shiftably carried in said frame in respective supporting arms, a guide substantially between said three rolls and adapted to carry clothes from the bite between said first roll and one of the shiftable rolls to the bite between said first roll and the other of said shiftable rolls to retain the guide in proper operative position when said rolls are shifted, a gear carried by each arm supported roll, a third gear carried adjacent said guide and in mesh with the other two, and links acting to maintain the three gears in operative relation for various positions of the rolls.

11. In a wringer, a frame, three rolls mounted in said frame with their axes triangularly spaced from each other to provide between said rolls a pair of roll bites, means to maintain wringing pressure between two of said rolls, means to shift said means to establish wringing pressure between one of said two rolls and the third roll, and release mechanism adapted to be actuated when a predetermined thickness of material is fed to the wringer to stop the operation of the wringer.

12. In a wringer, three rolls therein with their axes triangularly spaced apart and with one roll surface simultaneously in bite-establishing relation with the roll surfaces of each of the other two rolls, a pressure spring mechanism pivotally supported in said wringer and shiftable from a position creating heavy wringing pressure at one roll bite to a position creating wringing pressure at the other roll bite and resilient light pressure means normally urging both said other two rolls into bite establishing relation with said one roll.

13. In a wringer, a frame, three rolls mounted in said frame with their axes triangularly spaced from each other to provide between said rolls a pair of roll bites, means for maintaining wringing pressure between two of said rolls, means to shift said means to establish wringing pressure between one of said two rolls and the third roll and common means operable by either of the pressure applying rolls for stopping operation of the wringer upon feeding a predetermined thickness of material therethrough.

CHARLES W. WILLIAMS.
